UNITED STATES PATENT OFFICE.

ERNEST R. MITCHELL, OF PHILADELPHIA, PENNSYLVANIA, ASSIGNOR TO MITCHELL SPECIALTY COMPANY, OF PHILADELPHIA, PENNSYLVANIA, A CORPORATION OF PENNSYLVANIA.

DOOR BUMPER AND RETAINER.

1,212,663.

Specification of Letters Patent. Patented Jan. 16, 1917.

Application filed September 23, 1914. Serial No. 863,187.

To all whom it may concern:

Be it known that I, ERNEST R. MITCHELL, a citizen of the United States, residing in Philadelphia, Pennsylvania, have invented 5 a Door Bumper and Retainer, of which the following is a specification.

One object of my invention is to provide a strong, inexpensive, and substantial as well as relatively simple device for application to doors, casements and similar structures which shall act as a resilient stop or bumper, while at the same time holding the structure to which it is attached from accidental opening, the arrangement of parts 15 being such that my device shall be capable of supporting more or less of the weight of the door or window to which it is attached, or with which it is used.

Another object of the invention is to provide a device of the character described with 20 a resilient roller so mounted as to be capable of frictionally engaging two surfaces at right angles to each other upon the door or frame with which it is used in order that it may not only act to take a certain proportion 25 of the weight of the door off its hinges, but may also act as a stop as well as a holding means.

These objects and other advantageous ends 30 I secure as hereinafter set forth, reference being had to the accompanying drawings in which:—

Figure 1 is a perspective view illustrating my invention as applied to a vehicle door; 35 Fig. 2 is a horizontal section of my invention applied to the door shown in Fig. 1; Fig. 3 is a plan of the stamping from which the frame of my device is made; Fig. 4 is a perspective view of the stamping shown in 40 Fig. 3 after it has been formed, but prior to the mounting of the roller therein; and Figs. 5, 6 and 7 are front, back and end elevations of my invention.

In the above drawings, 1 represents a part 45 of a door frame and 2 a part of a door having a rabbeted edge. On the rabbet of this edge is mounted a metallic body 4 of the construction shown in Figs. 3 to 7 inclusive, in which is mounted a spindle 5 rotatably 50 carrying a rubber roller 6. While I prefer that this spindle shall be so fixed in the frame as to be held from rotation, it may be permitted to rotate, and though the roller 6 is preferably of rubber it is obvious that

other suitable material may be employed 55 without departing from my invention.

The body 4 consists of a rectangular piece of sheet metal having punched from it a central rectangular section so as to provide a hole 7. One side of this piece is then split 60 and the ends formed are bent back along the lines *a*—*a* Fig. 3 through an angle of 90 degrees so that they lie parallel to each other, after which they are again bent upon the lines *b*—*b*, causing one edge of each of them 65 to lie immediately adjacent and parallel with the adjacent end of the opening 7. In the two parallel ends 8 thus formed are holes 9 for the reception of the spindle 5 carrying the roller 6 so that its cylindrical surface 70 projects beyond the face 10 of the body as well as beyond the plane of the portions 11 at right angles thereto. By means of screws or other suitable holding means, the body is mounted with its face 10 flush with or parallel to the edge of the rabbet 13 and with its parts similarly flush with or parallel to the face 14 of said rabbet.

With this construction it is noted that when the door is moved to its closed position, the cylindrical surface of the roller engages the plane face 15 of the door jamb or post and as said door is moved inwardly, is rotated on or with its spindle 5, although more or less compressed, since the parts are 85 so proportioned that the distance between the face 10 of the body 4 and said face of the jamb is less than the amount of projection of the roller beyond said plate. Just before the door reaches its fully closed position the 90 roller engages the face 16 of the rabbet forming part of the door jamb and thus necessarily and without shock brings the door to rest. When in this position, two parts of the surface of the roller lying in 95 planes substantially at right angles to each other are frictionally engaged with the surfaces of the door jamb so that not only is the door held from moving out of its closed position, but, especially if a plurality of 100 rollers should be employed, there is provided a very material support for the door in addition to that given by its hinges. These latter are thus relieved of more or less strain and in addition the door is effectually prevented from rattling, since the resilient roller is more or less compressed. If desired, as shown in Fig. 2, the face 15 of the

door jamb may be recessed or under-cut so that the roller will spring into the recess as it approaches its closed position, but this may be omitted without departing from my invention and the face 15 be formed at right angles to the face 16. It is to be understood that it is immaterial whether the body 4 and its roller be mounted on the door or on the door jamb since in any case the action above described would be the same. Moreover, while I have described the invention as applied to a door, it will be understood that it may with advantage be applied to various forms of swinging or sliding structures such as windows, either of the casement or sliding sash forms, as well as to vehicle doors, etc. While therefore, I have employed the term door in the claims, this is intended to broadly cover closures of various forms as well as other structures, which it is desired, shall be stopped, held and supported as herein specified.

I claim:—

1. The combination of a frame; a door; a supporting structure mounted on one of said parts; and a resilient roller mounted on said structure with its axis parallel to that of

the door in position to simultaneously engage two surfaces substantially at right angles to each other on the other part when 30 the door is closed.

2. The combination of a frame; a door; one of said parts having at its edge two surfaces substantially at right angles to each other; and the other having a rubber roller 35 mounted with its axis parallel to that of the door in position to simultaneously engage both of said surfaces when the door is closed.

3. The combination of a frame; a door; rabbets respectively formed on two adjacent 40 edges of said door and frame; with a roller mounted on one of said members with its axis parallel to the lines of said edges and in a position for its cylindrical surface to simultaneously and yieldingly engage portions both of the rabbet and of the edge of the other member.

In testimony whereof, I have signed my name to this specification, in the presence of two subscribing witnesses.

ERNEST R. MITCHELL.
